UNITED STATES PATENT OFFICE.

CHARLES P. GLOVER, OF ATLANTA, GEORGIA, ASSIGNOR OF ONE-HALF TO THOMAS P. LEDEBETTER, OF ATLANTA, GEORGIA.

TOBACCO-USER'S APPLIANCE.

1,215,519.

Specification of Letters Patent. Patented Feb. 13, 1917.

Application filed June 21, 1916. Serial No. 104,978.

To all whom it may concern:

Be it known that I, CHARLES P. GLOVER, a citizen of the United States of America, residing at Atlanta, in the county of Fulton 5 and State of Georgia, have invented new and useful Improvements in Tobacco-Users' Appliances, of which the following is a specification.

The present invention relates to improvements in tobacco users' appliances, the device being known to the trade as a "plug jack," and is designed particularly for the purpose of detaching a plug or strip of tobacco from the mass of plug tobacco in 15 which it is boxed.

In packing tobacco in boxes in plug form, to be sold at retail by the plug, the mass of plugs is so compactly packed that it is frequently difficult to detach a plug from an 20 open box without danger of tearing or breaking the plug. This tearing or breaking, of course is not deleterious to the tobacco, but it mars the appearance of the plug and may render a sale impossible.

The purpose of the present invention is to provide a simple, handy, and comparatively inexpensive implement or tool known as a "plug jack" by which single plugs of tobacco may be detached from the mass in the open 30 box, with facility and without marring the appearance of the plug by tearing or breaking.

In the accompanying drawings I have illustrated one complete example of the 35 physical embodiment of my invention constructed according to the best mode I have so far devised for the practical application of the principles of my invention.

Figure 1 is a top plan view of an implement embodying the novel features of my invention.

Fig. 2 is a front end view of the implement.

Fig. 3 shows a side view of the implement in position for use.

The tool or implement 1 is preferably of cast steel, although it may be of other material such as stamped metal, and is provided at one end with a pair of spaced 50 prongs 2 and 3 forming between them the open space 4 and each formed with a sharp-

ened knife edge adapted to be pushed into the tobacco plug. While I have illustrated but two prongs, it will be understood that I contemplate varying the number of prongs 55 and they may be increased if desirable or necessary.

At the underside of the tool are located a pair of integral lugs 5, 5, which extends from the edge of the tool at the space 4 toward the rear a sufficient distance and project from the tool as required. These lugs are preferably formed with a curved front face 5' and the fulcrum points 6, to impinge against the tobacco and they serve to steady 60 the tool when it is being used.

In Fig. 3, three plugs P, P' and P^a are illustrated in the position they assume when packed in a box from which they are to be sold at retail, and the tool is shown in position to pull the plug P from the box. The two prongs have had their knife edges inserted diagonally into the plug and the fulcrum lugs are bearing against the face of the plug, but only at the fulcrum points or 75 bearing points 6, so that the tobacco will not be marred. Now when pressure is applied on the handle 1 the plug P is detached from the mass in the box with facility and despatch and the plug may be pulled from the 80 box and handled quickly in the sale without being marred in appearance.

The use of the plug jack or tool by the storekeeper, preserves the tobacco in a sanitary condition, because the tobacco may be 85 kept in its box until entirely sold out, thus protecting it from the dust or any foreign substances of the atmosphere.

Having thus described my invention, what I claim is:

A tobacco user's appliance comprising a handle with a pair of spaced, upturned end prongs fashioned with knife edge points to enter a tobacco plug and forming a space between them, and a pair of integral lugs at 95 the under side of the handle located at an angle thereto and each formed with a curved front face and a sharpened fulcrum point to bear against and penetrate the plug for the purpose described.

In testimony whereof I affix my signature.
CHARLES P. GLOVER.
